UNITED STATES PATENT OFFICE.

JOHANNES THEODORES SENTROP, JR., OF MONTREAL, QUEBEC, CANADA.

CYCLE.

• 1,390,822.

Specification of Letters Patent. Patented Sept. 13, 1921.

Application filed February 8, 1918. Serial No. 216,114.

To all whom it may concern:

Be it known that I, JOHANNES THEODORES SENTROP, Junior, a subject of the Queen of the Netherlands, and resident of the city of 5 Montreal, Province of Quebec, Canada, have invented certain new and useful Improvements in Cycles, and do hereby declare the following to be a full, clear, and exact description of same.

10 This invention relates to cycles such as motor-cycles and appertains particularly to the frame construction, the primary objects of the invention being as follows:

15 To provide an improved frame whereby the weight and strain are more efficiently sustained and uniformly distributed than heretofore and one which, while facilitating a ready and convenient removal of the wheels of the cycle, is also readily accommodated for the attachment of a wagon.

20 To provide an improved steering arrangement upon the principle of bodily swinging the steering wheel upon a rear pivot as distinguished from pivoting the steering wheel 25 about a point central thereof.

To provide a novel spring suspension.

The above with further objects and advantages will be hereinafter more fully described and particularly pointed out in the 30 appended claims.

For full comprehension, however, of my invention reference should be had to the accompanying drawings forming a part of this specification, in which the same reference characters indicate the same parts and wherein:

Figure 1 is a side elevation of my improved cycle frame;

Fig. 2 is a plan of same;

40 Fig. 3 is a side elevation of the front of the cycle drawn on a larger scale;

Fig. 4 is a plan of same, one half in horizontal section;

45 Fig. 5 is a view similar to Fig. 3 of the rear of the cycle;

Fig. 6 is a horizontal section of same taken on line 6—6 Fig. 5;

Fig. 7 is a part side elevation and part section of a modified construction of connection between the center and front section of the cycle frame;

Fig. 8 is a plan of same with portions broken away in horizontal section;

Fig. 9 is a side elevation illustrating the

attachment of the handle to the frame in 55 said modified construction illustrated in Figs. 7 and 8;

Fig. 10 is a vertical section on line 10—10 Fig. 11;

Fig. 11 is a plan of Fig. 9;

Fig. 12 is a front elevation of the cycle.

Referring now to the drawings, 2 indicates the front axle carrying the front wheel, and 3 the rear axle carrying the rear wheel.

The cycle frame extends continuously 65 from rear to front axles on both sides of the wheels, such frame consisting of a connected pair of top bars on either side of the wheels above the axles and disposed substantially parallel to each other along the general longitudinal line of the latter, and a bottom pair of similar bars in approximately the vertical plane of the top bars, spaced therefrom below the axles and connected to the top bars in parallelism therewith. 70

The frame is constructed in three sections; top preferably, parallel bars 4, bottom, preferably, parallel bars 5 and front and rear upright connecting bars or struts 6 constituting an open flat box-like central section capable of accommodating any type of cycle motor; top bars 7 continuing forwardly 80 from bars 4, bottom bars 8 extending forwardly from bars 5 and connected by front bars or struts 9 constituting a front section; top bars 10 continuing rearwardly from bars 4, bottom bars 11 continuing rearwardly from bars 5 and connected by rear bars or struts 12 and struts 12^a inclined rearwardly 85 from bottom to top bars, constituting a rear section. The front and rear sections extend out beyond the front and rear wheels respectively and the top and bottom bars of the frame, as a whole, extend in a substantially straight line thus presenting an effective guard in the event of a collision and transmitting and distributing weight and strain uniformly throughout the structure.

The gear box 27 inclosing gear 28 operatively connected to the rear wheels by drive 90 chain 29, is supported by straps 30 extending between the rear bars which effectively resist the strain to which the gear box is exposed. 95

The axles 2 and 3 are respectively supported at each end in a vertically slidable bearing plate 13 to which it is secured by nuts 13^a. Each bearing plate is located be-

tween a pair of guides or strut-like uprights 14 and 15 respectively carried by the frame, spaced longitudinally of the latter and presenting in their opposing edges longitudinal 5 grooves 16 within which the edges of the plates travel. The plates have outwardly extending ledges 17 below the axle bearing thereof, to each of which ledges the middle portion of a laminated spring 18 is bolted, 10 the ends of the spring being linked to the bottom bars of the front and rear sections of the frame and by yieldingly controlling movement of the sliding bearing plates provide a cushioning suspension for 15 the frame. The four springs suspending the frame are all similarly arranged and attached and are therefore interchangeable.

I prefer to incline the front uprights upwardly and rearwardly so as to more closely 20 align them with the direction of force exerted by an encounter of the front wheel with an obstacle thus insuring a cushioning action both vertically and longitudinally of the frame as the rearward inclination of the 25 guides enables the bearing plates to slide in both the vertical and longitudinal direction.

The inner upright 14 at each side of the front wheel extends between and is connected 30 to the top and bottom bars 7 and 8 while the outer upright 15 in front of upright 14 is bifurcated at its ends 19 which respectively straddle the bottom bar 8 and a bar 20 extending longitudinally between the 35 front bar 9 and the upright 14, being secured in position by nuts 21 which are screwed upon their respective bars and enable the upright 15 to be adjusted longitudinally of the frame to take up wear between 40 the uprights and the slidable plates. The bifurcated ends of the uprights 15 also enable them to be readily removed.

The same reference characters apply to the uprights 14 and 15 at the rear which are 45 constructed similarly to those at the front with the exception that in the preferred form they are curved at the center toward the front.

If it is desired to lower the frame from 50 the position indicated the bearing opening 23 can be utilized, while to elevate the frame from said position the springs can be secured to the upper side of the ledges 17 instead of beneath as shown or to secure a 55 greater degree of elevation the plates 13 may be reversed top to bottom thus positioning the ledges above the axle bearings of the plates. For this reversal of the plates the plate at one side of the rear wheel should 60 be substituted for that on the other side in view of the outstanding ledges 17.

Should either of the springs become broken and cannot be conveniently replaced, the link pins 24 of the spring can be removed 65 and inserted in holes 25 in the uprights 14

and 15 to engage either of a series of vertically spaced grooves 26 in the edges of the plate 13 and thus connect the wheel directly to the uprights, the grooves to be employed being determined by the elevation of frame 70 desired. Owing to this arrangement the cycle is not crippled by a broken spring as a substitute support can be quickly provided for during the change from one support to the other. 75

Should it be desired to elevate the frame at the front or rear end only this may be done by raising as above described the attachment of the front or rear spring suspension only or when it so happens that the 80 pins 24 are employed instead of the springs, by engaging such pins with those grooves 26 which will give the desired elevation.

The above described arrangement provides for the support of the weight by suspension 85 at a point below the horizontal center line of the cycle and, in most instances of adjustment, below the axles, thus insuring a very effective suspension and one wherein the weight is supported mainly at the lower 90 portion of the frame, thus materially assisting in the maintenance of equilibrium.

The cycle is steered by swinging the front wheel bodily upon a pivot at the rear of the latter instead of pivoting the wheel upon 95 its vertical center and for this reason the front section of the frame has a vertical pivotal connection with the central section, the top bars 7 terminating at their rear ends in a flat yoke 31 bearing upon a flat yoke 32 100 connecting the front ends of bars 4 and pivoted thereto by bolt 33, and the bottom bars 8 and 5 being similarly connected by yokes 34 and 35 and bolt 36.

A steering handle is attached to and enables the front frame section and wheel to be bodily swung horizontally on the pivot bolts 33 and 36, such handle comprising parallel sides 37 having lateral slots 38 formed by the bifurcated ends of a cross-piece 39 110 connecting the front ends of the sides 37. Each bifurcated end of the cross-piece enters between jaws 40 formed upon the bars 7 respectively of the front section and straddles a bolt 41 carried by said jaws, being clamped 115 between the jaws by nuts 42.

This connection between front section and handle is preferably disposed approximately in vertical line with axle 2, the sides 37 of the handle extending rearwardly to a point 120 just in front of pivot 33 where they are connected by a cross-piece 43. Each side 37 is mounted upon the yoke 31 by means of a downwardly depending arm 44 having a screw-threaded lower end, and an interiorly 125 threaded stud 45, the stud being screwed into a tapped hole in the yoke and secured by nut 46 and the arm being screwed into the stud and secured by nut 47. The sides 37 continue rearwardly from the pivot 33 in an 130

outward flare in the form of handle bars, a particular feature of the construction being that the handle is connected to the frame at approximately the pivot point of center 5 and front frame sections and also to the front section at a suitable point, thus insuring power and reducing torsional strain. A further feature of the construction illustrated is that the rear portion of the steering 10 handle is longer than the front portion, that is to say the handle, in extending past the pivot 33 preferably presents a longer lever arm in rear of said pivot than the distance between the latter and a point in vertical line 15 with the front axle, to facilitate the steering.

If desired the bars 4, 5 and 7, 8 can, as shown in Figs. 7 and 8, be pivotally connected at the front by a hollow cylindrical 20 standard 48, the before mentioned yokes 31, 32 and 34, 35, being connected by flanges 49 upon the cylinder and the latter extended upwardly and having a rotatable cap 50 to which the handle is connected.

25 The sides of both front and rear frame sections are constructed to swing outwardly, or to be taken out entirely, to permit of easy access to the wheels and for this reason I have formed horizontal slots 51 in the rear 30 ends of bars 7 and 8 and mounted bolts upon such ends and passing through said slots, the front ends of yokes 31 and 34 being vertically slotted at 53 and horizontally countersunk or grooved from side to side at 54. The 35 vertically slotted ends are located in the slots 51 and straddle the bolts 52 from the rear while a flat pin 54^a with slots or jaws 55 is inserted into grooves 54 and through slots 51 of the top bars 7 so that the slotted 40 pin will straddle the bolts 52 from the side and by its engagement in the grooves 54 lock the bars 7 and yoke 31 together in a pivotal manner, bolts 52 acting as the pivot and a prolongation 53^a of the bar beyond the slot 45 53 preventing inward swinging. The pin is held against accidental displacement by a stud 55^a loosely located in a hole in the edge of the pin near its end and normally held in a protruding position by a spring 50 56 or the like. When the pin is being placed into locking position the stud is displaced inwardly by engagement with the bottom walls of slots 51 and when carried beyond the far side of top bar 7 on the side opposite to 55 that from which the pin was inserted, the spring causes the stud to protrude beyond the side of the slot and normally prevent removal of the pin. Another of these pins 54^a is employed to lock the bars 8 to their yokes 50 60 34 in a similar manner to the upper connection.

The sides of the front section are normally connected at the front by a strap 57 which serves as a license plate or lamp 65 holder, such strap being connected to the

front bars 9 by bolts 58 carried by the bars, and entering slots 59 in the strap and clamping nuts 60 upon the bolts.

When it is desired to swing one side of the front frame outwardly, the nut 13^a upon that end of the axle is removed and nuts 42 and 60 upon that side loosened to free the frame side from the handle and the strap 57, after which the frame side can be swung outwardly and if desired utilized as a stand 75 for supporting the cycle by swinging the side to a position at about right angles to the frame and tilting the cycle until the front end of the swung out side bears upon the ground.

80 The pivotal connection between top bars 4 and 10 is provided as follows:—A vertical bolt hole 60^a is formed near the end of each bar 4 and communicates with a depression formed in the upper side of the bar from 85 side to side thereof, the rear wall 61 of the depression being horizontally curved and rearwardly beveled and the front wall 62 flat. The depression forms an upwardly projecting boss 63 at the end of the bar and 90 this boss is downwardly and rearwardly beveled from the curved wall 61 and rounded at 64 and provided with a projection forming an outwardly facing vertical shoulder 65 near the center of the boss. The front 95 end of each of the bars 10 is undercut to form a groove from side to side of the bar, the rear wall 66 of the groove being curved and beveled to correspond to the rounded end of the adjacent bar 4 and provided with a projection forming an inwardly facing vertical shoulder 67 near the center of the groove, the front wall 68 of the groove being curved and beveled to correspond to the rear wall 61 of the depression of the adjacent arm 4. The described groove forms a downwardly projecting boss 69 at the end of the bar and this 100 boss is vertically slotted at 70.

110 When the bars are connected the boss 69 is located in depression of bar 4 and boss 63 in groove of bar 10, the curved and beveled walls 61 and 68 forming a socket connection and the bosses being held against vertical displacement by a bolt 71 which, passing 115 through hole 60^a and slot 70, is secured by nut 72. When the bars are in alignment the vertical shoulders 65 and 67 engage and prevent inward swinging of the rear frame side while such side is limited to an outward 120 swing of slightly over 90° by the engagement of the side of the bar 10 with the flat wall 62 of the depression in bar 4.

The connection of bottom bars 5 and 11 of the rear section are similar to the connections just described and indicated by the same reference characters.

125 The sides of the rear frame section can therefore be swung outward similarly to the sides of the front section after removal 130

of the nut 13^a at the rear and removal of a rear connecting bar 73 which engages in slotted rear ends 74 of the bars 11 and are held in position by nuts 75.

5. A boring in the frame bar 11 may be provided, as at 99, to accommodate the axle of a stand for supporting the cycle when at rest should such be desired. The above described cycle is specially adapted for the attachment 10 of a wagon at the front or rear, the attachment being made in part by removing the front or rear wheel and substituting for it the axle of the wagon (not shown) and it will be seen that the swinging sides of the frame 15 permit of a ready removal or replacement of the rear wheel thus considerably facilitating the attachment or removal of the wagon or the like.

What I claim is as follows:

20. 1. In a cycle, the combination of wheels and a frame carrying the wheels, said frame including substantially parallel top bars on opposite sides of the wheels and in approximately the same plane at a point above the 25 axles of the wheels and substantially parallel bottom bars on either side of the wheels and in approximately the same plane at a point below the axles, the top and bottom bars at each side of the wheels being substantially parallel and in approximately the 30 same plane at the side of the wheels and extending beyond the said wheels.

2. In a cycle the combination of wheels and a frame carrying the wheels, said frame 35 extending beyond the said wheels and including substantially parallel top bars on opposite sides of the wheels and in approximately the same plane at a point above the axles of the wheels and substantially parallel bottom bars on opposite sides of the 40 wheels and in approximately the same plane at a point below the axles, the bottom and top bars at each side of the wheels being substantially parallel and in approximately the 45 same plane at the side of the wheels.

3. In a cycle the combination of wheels and a frame carrying the wheels, said frame including a central section, a rear section pivoted to the central section and a front 50 section pivoted to the central section, the frame being formed of substantially parallel top bars on opposite sides of the wheels and in approximately the same plane at a point above the axles of the wheels and substantially parallel bottom bars on either side of the 55 wheels and in approximately the same plane at a point below the axles, the bottom and top bars at each side of the wheels being substantially parallel and said front and rear sections extending longitudinally beyond the said wheels.

4. A cycle including a frame formed with central and end sections, one of said sections having a side member pivoted to swing 60 outwardly from the frame and a wheel hav-

ing a support carried by said pivoted member.

5. A cycle frame including a main section and sections adapted to have wheels mounted thereon, one of said wheel sections having sides respectively pivoted to the main section to swing outwardly therefrom. 70

6. A cycle frame having a central section, a rear section consisting of sides respectively pivoted to the central section to swing outwardly therefrom, and a front section consisting of sides respectively pivoted to swing outwardly from the central section. 75

7. In a cycle, front and rear wheels, a frame including a front section carrying the front wheel, such front section being pivoted to the remainder of the frame at a point in rear of the front wheel and a handle connected to the front section at points adjacent the pivotal connection and extending rearwardly past said pivotal connection, the portion of the handle in rear of the pivotal connection being greater than the portion of the handle in front of said connection. 80

8. In a cycle, front and rear wheels, a frame including a main section and a front section carrying the front wheel, such front section being pivoted to the main section at points in rear of the front wheel and a steering handle fulcrumed between its ends upon the front section and connected to the front section at a point distinct from and in advance of said fulcrum point. 90

9. In a cycle, a frame, pairs of spaced uprights carried by the frame, one of the uprights of each pair being adjustable to vary the space between it and the other upright of the pair, bearing plates slidably mounted between the uprights and wheels, the axles of which bear in said plates. 100

10. In a cycle, a frame, a wheel, bearing members for the wheel, said members being slidably mounted upon the frame to move vertically and means providing a fixed connection between the bearing members and frame, including correspondingly arranged openings in adjacent portions of the frame and having members for their combined reception and a securing pin. 110

11. In a cycle, a frame, a wheel, bearing members for the wheel, slidably mounted upon the frame to move vertically, said frame having holes therein and each of the bearing members having a series of vertically arranged openings therein adapted to 115 register when the bearing members and frame are to be secured together.

12. In a cycle, a frame, bearing plates carried by the frame to slide vertically with respect thereto, wheels carried by said plates, springs connected to frame and plates and yieldingly supporting the latter and means for varying with respect to the axles of the wheels, the points of connection between 120 springs and plates. 125

13. In a cycle, a frame, bearing plates carried by the frame and adapted to slide vertically with respect thereto, wheels carried by the plates and means for fixedly connecting the plates to the frame.
14. In a cycle, a frame, bearing plates carried by the frame and adapted to slide vertically with respect thereto, wheels carried by the plates and means for fixedly connecting the plates to the frame at varying heights.
15. In a cycle, a frame, bearing plates carried by the frame and presenting bearing openings at different heights with respect to the plates and a wheel the axle of which bears in one of the openings of the plate.
16. In a cycle, front and rear wheels and a frame carrying the wheels, and projecting beyond the front wheel and beyond the rear wheel.
17. A frame for a cycle including detachably connected sections, one of the sections presenting a vertically arranged slot and a horizontally arranged groove and the other section presenting a horizontally arranged slot inclosing the vertically arranged slot, a bolt carried by the horizontally slotted section and located in the vertical slot and a key located in said groove and straddling the bolt.
18. A frame for a cycle including pivotally connected sections, one of the sections presenting a depression upon its upper surface an upstanding boss adjacent the depression and a vertical outwardly facing shoulder a bolt carried by the depressed section, the other section straddling said bolt, being grooved on its underside to receive the upstanding boss and presenting a depending boss located in said depression and a vertical inwardly facing shoulder adapted to engage with said outwardly facing shoulder and a nut screwed upon the bolt and holding said sections together.
19. A cycle including wheels, a main section, an end section carrying one of said wheels and said end section including top bars and bottom bars on either side of the wheel and connected by a rear bar, struts inclined rearwardly from bottom to top bars, horizontally disposed bars and spaced uprights at each side of the wheel connecting the horizontally disposed bars and the bottom bars, and pivotal connections between the main section and the top and bottom bars respectively.
20. A cycle including wheels, a main section, an end section carrying one of said wheels and extending beyond the outer periphery of such wheel, said end section including top bars and bottom bars on either side of the wheel and connected by a rear bar, struts inclined rearwardly from bottom to top bars, horizontally disposed bars and spaced uprights at each side of the wheel connecting the horizontally disposed bars and the bottom bars, the rear ones of such spaced uprights being adjustable and all being curved at the center toward the rear, and pivotal connections between the main section and the top and bottom bars respectively.
21. A cycle including wheels, a main section and a front section carrying one of said wheels and extending beyond the outer periphery of such wheel, said front section including top bars and bottom bars on either side of the wheel and connected by a front bar, horizontally disposed bars and spaced uprights inclining rearwardly at each side of the wheel and connecting the horizontally disposed bars and the bottom bars, the front ones of such spaced uprights being adjustable, and pivotal connections between the main section and the top and bottom bars respectively.

In testimony whereof, I have signed my name to this specification.

JOHANNES THEODORES SENTROP, Jr.
